GAME

Alma M. Lassen, New York, N. Y.

Application May 19, 1937, Serial No. 143,610

3 Claims. (Cl. 273—161)

The object of this invention is to provide a novel and highly entertaining game of the fortune-telling type.

In the attached drawing:

5 Figure 1 is a view in perspective of the game pieces assembled in preparation for play;

Fig. 2 is a view in perspective illustrating the manner in which individual game pieces drawn at random from the assembly shown in Fig. 1 10 are joined together in the course of play, and

Fig. 3 is a view in perspective showing the game pieces so joined arranged in a typical fan formation.

With reference to the drawing, the game in 15 its physical embodiment comprises a set of pieces 1 of indeterminate number, these pieces taking the form in the present instance of flat elongated strips made of wood or of other suitable material. Each of the game pieces has at one end 20 an aperture 2, and is provided at the other end with a symbolic marking designated by the reference numeral 3, which in playing the game is interpretable either individually or in conjunction with the symbols of other pieces in terms 25 of augury. In the present instance, these markings appear on one face only of the strips, and each strip also carries on the same face a number, as illustrated, the numbers on the various pieces of the set running in the present instance 30 in sequence. In conjunction with the game pieces 1, a pin 4 is provided, preferably having a head 5 at one end, and this pin 4 is adapted to pass through the apertures 2.

In playing the game, the game pieces 1 are 35 assembled, as shown in Fig. 1, in a suitable receptacle 5 with their apertured ends projecting and with the other ends, which carry the symbols 3, hidden in the interior of the receptacle. Preferably the game is merchandised with the 40 game pieces enclosed in a container one portion of which is adapted to function as the receptacle 5. From this receptacle, a predetermined number of the game pieces of the set, say fourteen, are withdrawn at random and are assembled 45 about the common axis afforded by the pin 4, and when the pieces are so assembled on the pin, they may as shown in Fig. 3 be adjusted into different radial planes in fan formation, in which they may readily be retained by pressure 50 of the fingers. In this position, it will be apparent that all of the symbols are exposed to the view of the individual or individuals playing the game.

In conjunction with the game pieces 1 and 55 the pin 4, I preferably provide a legend sheet

or booklet in which the different symbols are listed by name and number, together with a possible or preferred interpretation of the individual symbols or groups of symbols in terms of augury. The engagement ring appearing on 5 the game piece numbered 3, for example, may be interpreted as a proposal of marriage, engagement in an enterprise, or a promise. The heart appearing on the game piece numbered 12 may be interpreted as indicating an affair of the 10 heart, or heart interest in an individual, or in an enterprise. The other symbols appearing on the game pieces shown in Fig. 3 may for example be interpreted, respectively, as follows:

15 Knot—No. 25. Binding. A contract.
Quill—No. 40. Writing. Signing of papers.
Cart—No. 28. By someone else's efforts—assistance rendered.
Bell—No. 9. Surprise. Opportunity knocking. 20 Or telephone message.
Broom—No. 30. To move, or change. Or a cleaning out.
Scales—No. 11. Something to be weighed in the balance. Temptation. Or justice.
Cornucopia—No. 26. Fruition of labored efforts. 25 Harvest.
Crane—No. 19. Stranger. Visitor.
Moon—No. 24. Night. Shadows.
Boat—No. 8. Ship. Travel by water.

30 The legend sheet or booklet will also contain suitable interpretation for the various other symbols which may appear upon the individual game pieces, so that a basis for interpretation is provided, it being possible, however, to modify these 35 interpretations or to employ entirely original interpretations of the different symbols if desired. The man and the woman appearing on game pieces numbered 1 and 2, respectively, may indicate the individual whose fortune is being told, 40 if of appropriate sex, or if not, may indicate a man or woman, as the case may be, in whom the said individual may be interested. The individual symbols may also have special connotations if they appear in the fan assembly in immediate proximity to other specified symbols. 45 If, for example, the game pieces 3 and 19 appear in the fan in contiguous relation, the proximity of the crane on the one marker to the ring on the other marker may indicate an infant. 50

The game is capable of numerous variations. After selection, for example, of the fourteen game pieces as set forth above and their assembly on the pin 4 into the fan formation, it may be required that the individual whose fortune is 55

- being told select that one of the exposed symbols in which he is most interested. By then counting seven pieces to the right, (returning to the left-hand end of the fan when the counting of this number goes beyond the last piece to the right), and from this point continuing the count of seven, always using the seventh piece as the new number 1, it is possible to select from the fourteen game pieces, and before again returning to the one originally selected and from which the count started, seven pieces of special significance. The symbols of these seven pieces may then be combined to produce a reading based upon the interpretations appearing on the legend sheet, or upon original interpretations made at the time of the reading.
- It will be apparent that the physical form of the game may vary considerably. The exact form or shape of the individual game pieces may vary without departure from the invention, it being only necessary in accordance with the invention to provide a means whereby a plurality of said pieces may be assembled in the typical fan formation, and to provide means also where-
25 by each of said markers differs in a visible respect from others of the markers. The markers may be of the same or differing colors as desired. It is apparent also that the means for joining the game pieces in the fan formation may vary considerably, although as a matter of simplicity and low cost of manufacture, the apertured pieces in conjunction with the pin 4 are desirable.
- 30 I claim:
- 35 1. A fortune-telling game comprising a set of

free elongated elements from which set may be drawn at random a sub-divisional number of said elements, and means for detachably assembling the elements of sub-divisional number about a common axis to extend from said axis radially in fan formation, said elements differing in visible respects from each other and each constituting a symbol having a specified augural meaning.

2. A fortune-telling game comprising a set of 10 free elongated game pieces from which set may be withdrawn at random a sub-divisional number of said pieces, each of said pieces having an aperture, a pin adapted for insertion through the apertures of the pieces of said sub-divisional 15 number to detachably unite said pieces by providing therefor a common axis from which said pieces may extend radially and in fan formation, said pieces differing in a visible respect 20 from each other and each constituting a symbol having a specified augural meaning.

3. A fortune-telling game comprising a set of free game pieces from which set may be withdrawn at random a sub-divisional number of 25 said pieces, each of said game pieces being in the form of a flat elongated strip and having at one end an aperture and at the other end a symbolic mark having a specified augural meaning, and a pin adapted for insertion through the apertures of the pieces of said sub-divisional number to detachably unite said pieces by providing therefor a common axis about which said pieces may extend radially and in fan formation. 30
